R. D. Turrentine

By *R. D. Turrentine* Attorney

UNITED STATES PATENT OFFICE.

ROBERT D. TURRENTINE, OF CLARKSVILLE, TENNESSEE.

DESIGN FOR A PENNANT.

61,125.

Specification for Design. Patented June 20, 1922.

Application filed April 29, 1921. Serial No. 465,543. Term of patent 7 years.

To all whom it may concern:

Be it known that I, ROBERT D. TURRENTINE, a citizen of the United States, residing at Clarksville, in the county of Montgomery and State of Tennessee, have invented a new, original, and ornamental Design for a Pennant, of which the following is a specification, reference being had to the accompanying drawing, forming part thereof.

The figure is a plan view of a pennant, showing my new design.

I claim:

The ornamental design for a pennant, as shown.

ROBERT D. TURRENTINE.

Witnesses:

MISS GENIE WOODSON,
BEN T. PASCHALL.
